BABY TEETHER

Robert M. Hayes, Weston, Mass.

Application April 18, 1952, Serial No. 19,387

Term of patent 14 years

(Cl. D83—1)

To all whom it may concern:

Be it known that I, Robert M. Hayes, a citizen of the United States, residing at Weston, in the county of Middlesex and State of Massachusetts, have invented a new, original, and ornamental Design for a Baby Teether, of which the following is a specification, reference being had to the accompanying drawing, forming a part hereof wherein

Fig. 1 is an elevational view of a baby teether, showing my new design; and

Fig. 2 is a side elevational view thereof.

I claim:

The ornamental design for a baby teether, as shown.

ROBERT M. HAYES.
